REMOTE CONTROL FOR SWITCH THROW-
ING DEVICES

Albert J. Gurney and Glenn D. Gurney, Canton,
Ohio, assignors to The American Mine Door
Company, Canton, Ohio, a corporation of Ohio

Application December 24, 1938, Serial No. 247,690

13 Claims. (Cl. 200—50)

The invention relates to remote controls for operating a switch throwing device of the general type disclosed in Gurney Patent No. 1,843,766, dated February 2, 1932, and more particularly to an overhead hand switch for controlling such devices.

Switch throwing devices, such as the present invention is adapted to operate, are commonly used for operating rail switches in mine railways and the like and the control devices now in general use for such purposes are in the form of a double pole hand switch located overhead and adapted to be manually operated by the motor runner as the train or locomotive passes beneath the same.

As the operator is thus upon a moving train while the manually operated switch is located at a stationary point, the manual operation of the switch must be accomplished rapidly as the locomotive moves beneath the same.

For this reason it is necessary for the operator to strike the handle of the control switch with his hand as he passes the same and it frequently happens that the operator does not strike the handle with sufficient force to throw the switch entirely to the closed position and as a result, the switch throwing device is not operated and a violent arc is produced in the controlling switch.

It also frequently happens that the operator strikes the switch handle with so much force that the switch blade will rebound to the opposite contact often resulting in operating the switch throwing device in the wrong direction as well as causing a violent arc in the controller switch.

The object of the present improvement is to provide a manually operated controlling switch so constructed and arranged that whenever the operating handle is thrown in either direction contact will be made to operate the switch throwing device in the proper direction.

A further object is to provide a controlling switch of this character in which the blade of the switch will be held in contact until the switch throwing device has operated.

A still further object is to provide a controlling switch of this character which only makes but does not break the circuit so as to avoid any arcs during the operation of the switch.

Another object is to provide a controlling switch of this character provided with a coil in series with the coils of the switch throwing device for holding the contact blade of the controlling switch in contact until the switch throwing

device has operated to throw the heavy rail switch.

Still another object is to provide a controlling switch of this character having two switch blades adapted to operate the switch throwing device in opposite directions with means for preventing either switch blade from being moved to operative position after the other blade has started to move toward contact, and provided with interlock means for holding each switch blade out until the other blade has been released.

A still further object of the improvement is to provide a controlling switch having a manually operated handle which may swing back after operation without breaking the circuit already closed or allowing the other circuit to be closed.

Another object of the invention is to provide a depending, peripheral bead upon the base surrounding the rotatable ring portion of the operating handle, to act as a drip molding in damp or wet locations.

The above objects together with others which will be apparent from the drawings and following description or which may be later referred to may be attained by constructing the improved remote control switch in the manner illustrated in the accompanying drawings, in which

Figure 1 is a bottom plan view of the improved remote control switch with parts broken away for the purpose of illustration;

Fig. 2, an enlarged fragmentary plan sectional view showing the switch blades or arms and associated parts;

Fig. 3, a detached perspective view of one of the switch blades or arms;

Fig. 4, an enlarged transverse sectional view taken as on the line 4—4, Fig. 1; and

Fig. 5, a wiring diagram of the improved remote control switch and switch throwing device which it operates.

Similar numerals refer to similar parts throughout the drawings.

The remote control switch mechanism may be mounted upon a metal base in the form of a disk 45 10 provided with ears 11 having apertures 12 therein for attaching the same to any suitable overhead support.

A depending peripheral bead 13 is formed upon the base plate 10 extending entirely around 50 the same, and at one point a depending arcuate flange 14 is formed thereon and spaced inwardly from the bead 13.

An electro-magnet 15 may be mounted upon the base plate 10 adjacent to the center of the arcuate flange 14, each pole piece thereof being

in the form of an angular bracket 16 of electrical iron forming a magnetic circuit of high permeability except for the air gap between the in-turned ends of the brackets.

A pair of pivoted arms, each comprising a combined switch blade and armature, are located adjacent to the magnet as indicated at 17, and each of these arms is pivoted as at 18 upon the base plate 10.

These arms may include a casting of bronze or other non-magnetic material indicated generally at 19 having the bearing boss 20 and the extension 21 provided with a lug 22, the armature being carried by this extension and being in the form of an iron plate 23 loosely mounted upon the extension as by the pivot 24, and the stud 25 of smaller diameter than the aperture 25a in the plate, allowing the armature to adapt itself to the pole pieces 16. This plate has a vertical flange 26 adapted to contact the angular ends of the iron pole pieces 16 upon the magnet.

An insulation plate 27, of Bakelite or the like may be attached to the projection 28 upon the bearing boss 20 as by screws 29 and provided with an angular flange 30 to which is attached a spaced pair of spring fingers 31, of laminated spring steel and copper or the like, each having a contact plate fixed to its outer end.

Both of the arms 17 are of the same construction but the positions thereof are reversed and the armature plate 23 is on the top of one arm and on the underside of the other arm.

An ear 33 is formed upon each of the arms 17, extending to the other side of the pivotal point from the extension 21, and a coil spring 34 is connected at one end to each ear and its opposite end is connected to the arcuate flange 14 of the base plate as indicated at 35.

An insulation block 36 is fixed upon the base plate 10 adjacent to each arm 17 and provided with a spaced pair of contacts 37 for engagement with the contact plates 32 of the corresponding arm 17.

The operating handle comprises a ring portion 38 rotatable within the bead 13 and having diametrically opposite hollow bosses 39 to which are connected the handles 40 which may be of wood or insulation material, and this ring has formed thereon or fixed thereto a bottom wall or web 41 having a hub portion 42 pivoted or journaled upon a central bolt 43 fixed to the base plate 10.

This hub portion has an angular extension 44 formed on the side opposite to the magnet 15 and arms 17 and terminating in a straight edge 45 engaged by the spring pressed plate 46 which has a guide portion 47 slidably mounted between the guides 48 fixed upon the base plate 10, a coil spring 49 being interposed between the sliding plate 46 and the bracket 50 at the outer end of the guides 48 for holding the sliding plate 46 against the straight edge 45 of the extension 44.

The sliding plate 46 may also have the forwardly extending guide fingers 51 slidably located around opposite sides of the bushing 52 located between the hub 42 and the pivotal bolt 43.

A pair of oppositely disposed spring fingers 53 are connected to the hub 42, one of said fingers being adapted to contact the lug 22 upon each switch arm 17, when the handle is oscillated around the pivot 43, in order to move the armature plate 23 of said arm toward the magnet 15 and to simultaneously move the contacts 32 of said arm into engagement with the fixed contacts 37.

It will thus be seen that as the handle 40 is os-

cillated in either direction, one of the arms 17 will be swung upon its pivot to bring the armature thereof into the range of the magnet 15 as the movable contacts 32 upon said arm engage the corresponding fixed contacts 37.

As will be clearly seen from an inspection of Fig. 4, the castings 19, forming a part of each arm 17, are so positioned that although their upper and lower edges are in slightly different horizontal planes, the greater portion of each arm lies in the same horizontal plane as the other arm, so that only one arm at a time may assume the closed position adjacent to the magnet 15.

With one arm 17 moved to operative position 15 as shown in Fig. 2, it will be seen that the other arm is held out so that even though the handle is struck with considerable force and rebounds in the opposite direction, the contact will not be broken and no contact can be made on the other side.

The wiring is shown in the diagram in Fig. 5 in which the trolley wire for the mine railway is indicated at 54, the improved remote control switch is indicated generally at 55 and the rail switch throwing device, such as disclosed in Patent No. 1,843,766 above referred to, is indicated generally at 56.

The wire 57 leads from the trolley wire 54 to the magnet 15 and a wire 58 leads from the magnet to one of the spaced fixed contacts 37 of each pair.

The other contact 37 of each pair is connected by a wire 59 with one of the spaced fixed contacts 60 of each pair in the switch throwing device. The other spaced fixed contact 61 of each pair is connected by a wire 62 or 62a with one of the solenoids 63 or 63a respectively, of the switch throwing device.

If signal lights are desired, a pair of contacts 40 64 adapted to be alternately engaged by the switch blade 65 of the switch throwing device are connected by wires 66 to the signal lights 67 which are also connected to the trolley wire 54 as by the wire 68.

In the operation of the improved remote control switch, it will be seen that when the handle is thrown in either direction, it will immediately bring the corresponding movable contacts 32 into contact with the corresponding pair of spaced contacts 37.

At the same time the corresponding armature 23 will be moved toward the magnet 15 which will be energized by the closing of the contacts 32-37, holding the switch arm in this position.

Assuming the parts to be in the position shown in the diagram in Fig. 5, in order to operate the switch throwing device to throw the switch in the opposite direction, the handle of the remote control switch is operated to move the right hand switch arm in position to close the circuit through the right hand pair of contacts 37.

The instant this happens the magnet 15 is energized as the circuit is then completed through the same from the trolley wire 54 through the wire 57, magnet 15, wire 58, contacts 32-37 at the right side of the diagram, wire 59 at the right side of the diagram, contact 60, switch blade 65 and contact 61 at the right side of the switch throwing device, wire 62a, coil 63a to ground.

As the magnet 15 is energized it will attract and hold the armature 23 of the switch arm which has been operated, so as to hold the switch blade thereof in closed position. The coil 63a will at the same time be energized operating the

switch throwing device in the manner described in Patent No. 1,843,766 above referred to and throwing the switch blade 65 of the switch throwing device into the opposite position breaking the circuit to the magnet 15 and permitting the switch arm 17 to be thrown back to inoperative or open position by means of the corresponding spring 34.

It will thus be seen that the improved remote control switch will operate much more satisfactorily and positively than the switches now in general use, that it cannot be operated in the wrong direction and cannot produce an arc since the switch blade contacts 32 only make but do not break the circuit.

We claim:

1. A control switch including an electro-magnet located in two normally open circuits, a pair of opposed switch arms located in substantially the same plane as each other and pivoted intermediate their ends upon spaced, parallel pivots, contact means at one end of each arm for closing one of the circuits and an armature movably mounted upon the other end of each arm, an operating handle pivotally mounted intermediate its ends, independently of the switch arms upon a pivot parallel to the switch arm pivots, oppositely disposed spring fingers upon the central portion of the handle adapted to selectively contact the corresponding switch arms to swing either switch arm upon its pivot to move the contact means thereon to circuit closing position and to simultaneously move the corresponding armature into the range of the magnet.

2. A control switch including an electro-magnet located in two normally open circuits, a pair of opposed switch arms located in substantially the same plane as each other and pivoted intermediate their ends upon spaced, parallel pivots, contact means at one end of each arm for closing one of the circuits and an armature movably mounted upon the other end of each arm, an operating handle pivotally mounted intermediate its ends, independently of the switch arms upon a pivot parallel to the switch arm pivots, oppositely disposed spring fingers upon the central portion of the handle adapted to selectively contact the corresponding switch arms to swing either switch arm upon its pivot to move the contact means thereon to circuit closing position and to simultaneously move the corresponding armature into the range of the magnet, and means upon the switch arms for preventing each switch arm from being operated when the other switch arm is in the operated position.

3. A control switch including an electro-magnet located in two normally open circuits, a pair of opposed switch arms located in substantially the same plane as each other and pivoted intermediate their ends upon spaced, parallel pivots, contact means at one end of each arm for closing one of the circuits and an armature movably mounted upon the other end of each arm, an operating handle pivotally mounted, intermediate its ends, independently of the switch arms upon a pivot parallel to the switch arm pivots, oppositely disposed spring fingers upon the central portion of the handle adapted to selectively contact the corresponding switch arms to swing either switch arm upon its pivot to move the contact means thereon to circuit closing position and to simultaneously move the corresponding armature into the range of the magnet, and means for returning the operating handle to

normal position while the operated switch arm remains in the closed position.

4. A control switch including an electro-magnet located in two normally open circuits, a pair of opposed switch arms located in substantially the same plane as each other and pivoted intermediate their ends upon spaced, parallel pivots, contact means at one end of each arm for closing one of the circuits and an armature movably mounted upon the other end of each arm, an operating handle pivotally mounted intermediate its ends, independently of the switch arms upon a pivot parallel to the switch arm pivots, oppositely disposed spring fingers upon the central portion of the handle adapted to selectively contact the corresponding switch arms to swing either switch arm upon its pivot to move the contact means thereon to circuit closing position and to simultaneously move the corresponding armature into the range of the magnet, means upon the switch arms for preventing each switch arm from being operated when the other switch arm is in the operated position, and means for returning the operating handle to normal position while the operated switch arm remains in the closed position.

5. A control switch including an electro-magnet located in two normally open circuits, a pair of independently pivoted switch arms one for closing each circuit, an independent armature upon each switch arm, and a common operating handle pivotally mounted independently of the switch arms under a pivot parallel to the switch arm pivots and adapted to be operated to selectively engage either switch arm to move the same to circuit closing position and simultaneously move the corresponding armature into the range of the magnet.

6. A control switch including an electro-magnet located in two normally open circuits, a pair of independently pivoted switch arms one for closing each circuit, an independent armature upon each switch arm, an operating handle pivotally mounted independently of the switch arms upon a pivot parallel to the switch arm pivots and adapted to be operated to selectively engage either switch arm to move the same to circuit closing position and simultaneously move the corresponding armature into the range of the magnet, and means for preventing each switch from being operated when the other switch arm is in the operated position.

7. A control switch including an electro-magnet located in two normally open circuits, a pair of independently pivoted switch arms one for closing each circuit, an independent armature upon each switch arm, an operating handle pivotally mounted independently of the switch arms upon a pivot parallel to the switch arm pivots and adapted to be operated to selectively engage either switch arm to move the same to circuit closing position and simultaneously move the corresponding armature into the range of the magnet, and means upon the switch arms for preventing each switch from being operated when the other switch arm is in the operated position.

8. A control switch including an electro-magnet located in two normally open circuits, a pair of independently pivoted switch arms one for closing each circuit, an independent armature upon each switch arm, an operating handle pivotally mounted independently of the switch arms upon a pivot parallel to the switch arm pivots and adapted to be operated to selectively engage either

switch arm to move the same to circuit closing position and simultaneously move the corresponding armature into the range of the magnet, and means for returning the operating handle to normal position while the operated switch arm remains in closed position.

9. A control switch including an electro-magnet located in two normally open circuits, a pair of switch arms independently pivoted intermediate their ends at spaced points and each having contact means at one end for closing one of the circuits and an independent armature at its other end, and an operating handle pivotally mounted intermediate its ends independently of the switch arms upon a pivot parallel to the switch arm pivots and adapted to be operated to selectively engage either switch arm to swing the switch arm upon its pivot to move the contact means thereon to circuit closing position, and simultaneously move the corresponding armature into the range of the magnet.

10. A control switch including an electro-magnet located in two normally open circuits, a pair of switch arms independently pivoted intermediate their ends upon spaced pivot points and each having contact means at one end for closing one of the circuits and an independent armature at its other end, a common operating handle mounted independently of the switch arms and adapted to be operated to selectively engage either switch arm to swing the switch arm upon its pivot to move the contact means thereon to circuit closing position and simultaneously move the corresponding armature into the range of the magnet, and means for preventing each switch arm from being operated when the other switch arm is in operated position.

11. A control switch including an electro-magnet located in two normally open circuits, a pair of switch arms independently pivoted intermediate their ends upon spaced pivot points and each having contact means at one end for closing one of the circuits and an independent, movably mounted armature at its other end, a common operating handle mounted independently of the switch arms and adapted to be operated to selectively engage either switch arm to swing the switch arm upon its pivot to move the contact means thereon to circuit closing position and

simultaneously move the corresponding armature into the range of the magnet, and means for returning the operating handle to normal position while the operated switch arm remains in closed position.

12. A control switch including a base plate, an electro-magnet mounted on the base plate and located in two normally open circuits, a pair of switch arms independently pivoted intermediate their ends at spaced points upon the base plate and each having contact means at one end for closing one of the circuits and an independent, movably mounted armature at its other end, spring means for normally holding the switch arms in open position, an operating handle pivoted intermediate its ends upon the base plate and adapted to be operated to selectively engage either switch arm to swing the switch arm upon its pivot to move the contact means thereon to circuit closing position and simultaneously move the corresponding armature into the range of the magnet, and spring means for returning the operating handle to the initial position while the operated switch arm remains in closed position.

13. A control switch including a base plate, an electro-magnet mounted on the base plate and located in two normally open circuits, a pair of switch arms pivoted intermediate their ends at spaced points upon the base plate and each having contact means at one end for closing one of the circuits and an independent, movably mounted armature at its other end, spring means for normally holding the switch arms in open position, an operating handle pivoted intermediate its ends upon the base plate and adapted to be operated to selectively engage either switch arm to swing the switch arm upon its pivot to move the contact means thereon to circuit closing position and simultaneously move the corresponding armature into the range of the magnet, spring means for returning the operating handle to the initial position while the operated switch arm remains in closed position, and an annular bead upon said base plate and a ring attached to the operating handle and rotatable within said bead.

ALBERT J. GURNEY.
GLENN D. GURNEY.
